SAFETY SHIELD FOR MOWERS AND OTHER GROUND TRAVERSING IMPLEMENTS AND THE LIKE

Robert C. Comer, Hopkins, Minn., assignor to The Toro Company, South Minneapolis, Minn.

Filed Apr. 21, 1972, Ser. No. 246,501

Term of patent 14 years

Int. Cl. D15—93

U.S. Cl. D40—1 A

FIG. 1

FIG. 4

FIG. 2

FIG. 5

FIG. 3

FIG. 1 is a perspective view as viewed from the top and side thereof, of a safety shield for mowers and other ground traversing implements and the like embodying my new design;

FIG. 2 is a top plan view thereof;

FIG. 3 is a front elevational view thereof, the rear elevational view corresponding to this view;

FIG. 4 is a bottom plan view thereof; and

FIG. 5 is a side elevational view thereof, the view from the opposite side corresponding to this view.

I claim:

The ornamental design for a safety shield for mowers and other ground traversing implements and the like, substantially as shown.
